UNITED STATES PATENT OFFICE.

JOSEPH F. RADEY, OF CATO, WISCONSIN.

PUMPING ATTACHMENT.

1,389,783.

Specification of Letters Patent.

Patented Sept. 6, 1921.

Application filed May 25, 1920. Serial No. 384,104.

To all whom it may concern:

Be it known that I, JOSEPH F. RADEY, a citizen of the United States, and resident of Cato, in the county of Manitowoc and State of Wisconsin, have invented certain new and useful Improvements in Pumping Attachments; and I do hereby declare that the following is a full, clear, and exact description thereof.

10 My invention relates to new and useful improvements in pumping attachments whereby a pump may be selectively operated by either manual or mechanical means.

In most pumps having but a single discharge spout, it is comparatively easy to selectively connect the pump rod with hand actuated means or with power means. When, however, the pump has a pair of outlet spouts, either one of which may be used, 20 or if the single spout is located at a considerable height above the ground, it is comparatively difficult under normal conditions and with standard apparatus to selectively connect the pump rod to the hand actuated driving rod or to the power driven actuating rod. This is occasioned by the fact that it is necessary to locate the means for connecting the pump rod with either of its driving rods at a point above the uppermost 30 discharge spout.

Consequently it is the primary object of this invention to provide a simply constructed selective connecting means which can be readily operated at a remote point to 35 attach either the manually driven or the power driven operating rod to the pump rod.

An additional object of the invention is to provide an apparatus of this character 40 which may be constructed of a comparatively few number of parts, all of which are compactly arranged.

It is still another object of the invention to provide yieldable connecting arms for 45 attaching the pump rod to either the manually driven operating rod or the power driven operating rod irrespective of whether or not said arms are alined with the arm receiving portions of the latter and at the 50 time that the element carrying said arms is shifted.

With these general objects in view the invention consists in the novel features of construction, combination and arrangement 55 of parts which will be hereinafter more par-

ticularly described and claimed and shown in the accompanying drawings, wherein:

Figure 1 represents a side elevational view of portions of a pump having two discharge spouts and showing certain features of the invention associated therewith.

Fig. 2 is a similar view, partly in section, of a portion of the pumping structure located above the parts illustrated in Fig. 1.

Fig. 3 is a horizontal section taken on the plane of the line 3—3 of Fig. 1.

In Figs. 4 and 5 are similar views taken substantially on the planes of the lines 4—4 and 5—5 of Fig. 2.

Although this improved apparatus is 70 preferably used in connection with windmills, it having been primarily designed for such purpose, it will be seen from the drawings and from the following description that the principles of the invention may well be 75 used in other relations, it being the primary object of the invention to provide means for selectively connecting the pump rod with a manually actuated operating rod or with a power actuating operating rod regardless of 80 the source from which the power is obtained. Likewise various changes may be made in the form and proportion of the different parts of the apparatus without departing 85 from the principles of the invention or sacrificing any of its advantages.

Referring more particularly to the drawings, the reference character 1 designates a pump stock having a pump rod 2 reciprocable therein and provided with a lower discharge spout 3 relatively close to the ground. The stock is extended a considerable distance above the ground as shown at 4 and has a second or upper discharge spout 5 located at its upper end. The spout 3 is provided with a cut-off cock 6 so that when closed water will be forced upwardly through the extension to the uppermost discharge spout 5. The pump stock 1 or the extension 4 carries a bracket 7 having a 100 handle 8 mounted thereon for manual operation.

The handle 8 is connected with a pitman 9 as is customary, the same in the present instance extending upwardly to a considerable height and having its upper end portion slidably in guides 10 carried by a frame 11. The bracket 7 also has a guide 12 slidably receiving the lower end portion of the pitman 9. The guides 10 of the frame 11 110

form parts of horizontal guide plates 13 which have their opposite ends connected with upright bars 14, these parts together comprising the main elements of the 5 frame 11.

Guides 15 are also carried by the plates 13 and are adapted to have the lower end portion of a power driven pumping shaft 16 slide therethrough, this shaft as herein- 10 after indicated being connected with a wind-mill or any other power producing means. Likewise the upper end of the pump rod 2 is also slidable through guides 17 carried by the plates 13. In the present instance the 15 pump rod is located between the pitman 9 and pumping shaft 16 and parallel, or substantially parallel to both.

The pitman 9 adjacent its upper end has a seat notch 18, and the pumping shaft 16 adjacent its lower end has a similar notch 19, both of these notches being adapted to receive connecting arms 20. A connecting arm carrying bracket 21 is secured upon the upper portion of the pump rod and has the 25 connecting arms 20 hinged thereto as at 22, these arms being extended in substantially opposite directions and toward the pitman 9 and pumping shaft 16 respectively. A leaf spring 23 is carried by the bracket 21 and has 30 its opposite ends engaging the arms 20 to urge the same in one direction, said spring normally causing abutment shoulders 24 on the said arms 20 to be engaged with similar shoulders 25 on the bracket. The bracket 21 35 while being carried by the pump rod 2 is slidable on a shift rod 26, the opposite ends of which are carried by a crank 27 and the arm 28 of a bell-crank 29 respectively. The shift rod is spaced from and parallel with 40 the axis of the pump rod 2 so that said shift rod is moved orbitally when the bracket 21 is shifted.

The bell-crank 29 to which the lower ends of the shift rod 26 is secured is rocked upon 45 oscillation of an operating sleeve 30, the same including a crank finger 31 which moves between the furcations of the other arm 32 of the bell-crank 29. Compactness of parts in this apparatus is procured by having the bracket 21, the crank 27 and the bell- 50 crank 29 movable about the axis of the pump rod 2 and the pitman 9 reciprocable within the rotatable sleeve 30.

As indicated most clearly in Figs. 1 and 3, 55 the operating sleeve 30 is shiftable to either one of three positions, in one of which positions both of the arms 20 are held out of cooperation with both of the seat notches 18 and 19, or in other words spaced from the pitman 60 and pumping shaft, this location of the different parts being depicted in the drawings. In another position of the sleeve 30, one of the arms 20 is engaged in the notch 18 and the other arm 20 is spaced from the pumping 65 shaft 16, while in the third position the last

mentioned arm 20 is located in the notch 19 and the first mentioned arm 20 is spaced from the pitman 9. The sleeve 30 is selectively moved to any one of these three positions by means of a handle 35, one end of which is 70 bifurcated as in 36 to straddle said sleeve and is pivoted thereto to swing vertically.

At the lower end of the sleeve 30 is a 75 guide plate 37 through which the pitman 9 is reciprocable and which carries a quadrant 38. This quadrant has three spaced seats 39 for receiving a rib 40 upon the handle 35. When this rib is located in either of these seats 39, the sleeve 30 and consequently the bracket 21 is locked against movement. 80

When the handle 35 is shifted from its neutral position as in Fig. 3 toward the positions indicated by the reference letters A and B, the sleeve 30 will be rotated and likewise the crank finger 31. The oscillation of 85 the crank finger 31 being imparted to the bell-crank 29 will move the shift rod 26 orbitally as hereinbefore mentioned. One of the arms 20 will thus be engaged either with the pitman 9 or the pumping shaft 16, 90 and if the notch 18 or the notch 19 is alined with this arm when the handle 35 is shifted, said arm will be received therein. If, on the other hand, the arm is not alined with its notch when said handle is shifted, it will engage the pitman 9 or the pumping shaft 16, 95 as the case may be, and yield against the tension of the spring 23, the abutment shoulders 24 and 25 being then out of contact. But, as soon as alinement of these parts is 100 procured, the arm will snap into its said notch and be retained therein to lock the pump rod to one of its actuating members until the handle 35 is again shifted toward 105 neutral position. As a result of this construction the pump rod may be easily and quickly connected with either the pitman 9 or the pumping shaft 16 regardless of the height of these parts above the ground. 110

I claim:

1. In an apparatus of the class described, a reciprocable operating device, a power driven actuating member, a manually driven actuating member, and means for selectively connecting either of the members with the operating device comprising a pivoted bracket, means on the bracket for selectively co-operatively engaging either of said members when the former is swung to either one of two positions, a crank, a rod connecting the crank and bracket, a rotatable member and a connection between the rotatable member and crank to oscillate the latter by rotation of the former. 115

2. In an apparatus of the class described, 120 a reciprocable operating device, a power driven actuating member, a manually driven actuating member, said members each having an arm receiving portion, and means for selectively connecting either of the members 130

with the operating device comprising a pivoted bracket, a pair of connecting arms carried by the bracket for selectively co-operatively engaging with either of said arm receiving portions when the former is swung to either one of the two positions, a crank, a rod connecting the crank and bracket, a rotatable member, and a connection between

the rotatable member and crank to oscillate the latter by rotation of the former. 10

In testimony that I claim the foregoing I have hereunto set my hand at Cato, in the county of Manitowoc and State of Wisconsin.

JOSEPH F. RADEY.
